H. H. PAYNE,
EJECTOR MECHANISM FOR DROP DOWN GUNS.
APPLICATION FILED AUG. 21, 1919.

UNITED STATES PATENT OFFICE.

HARRY HERBERT PAYNE, OF BIRMINGHAM, ENGLAND, ASSIGNOR OF TWO-THIRDS
TO JOHN WHITE, OF BIRMINGHAM, ENGLAND.

EJECTOR MECHANISM FOR DROP-DOWN GUNS.

1,386,275.

Specification of Letters Patent.

Patented Aug. 2, 1921.

Application filed August 21, 1919. Serial No. 319,026.

To all whom it may concern:
Be it known that I, HARRY HERBERT PAYNE, a subject of the Kingdom of Great Britain, residing at 30 Bristol road, Bournbrook, Birmingham, in the county of Warwick, England, gunsmith, have invented certain new and useful Improvements in or Relating to Ejector Mechanisms for Drop-Down Guns, of which the following is a specification.

According to the present invention the spring which exercises the ejecting effort is adapted to be "charged" or constrained upon the opening of the gun; said spring is thus under all normal conditions in the "un-charged" condition.

In carrying out the present invention I pivot to that part of the gun known as the fore-end which is located below the barrel to move therewith, a lever which is controlled by a spring, and which lever is adapted to be actuated by a part carried by the frame or body of the gun. This actuating part coöperates with the hammer and when the latter has been impelled to strike the cartridge the said actuating part is caused to project in such a manner that upon opening the gun the lever above mentioned is first rocked against the resistance of its control spring and subsequently released and under the influence of its spring returned to its initial position, thereby actuating the ejector.

In order that this invention may be clearly understood and readily carried into practice, reference may be had to the appended explanatory sheets of drawings, upon which:—

Figure 1 is a central longitudinal sectional view of a portion of the stock and of the barrel of a drop-down gun provided with an ejector mechanism constructed in accordance with the present invention, and showing the barrel in closed position.

Fig. 2 is a similar view of the same, showing the barrel in broken or open position.

In a convenient embodiment of the present invention I employ a hammer 4, such as is described in my concurrent application Serial No. 319,025 of even date herewith, comprising a vertically disposed block located in a cavity in the rear face of the frame or body, said block carrying the firing pin and being also combined with a telescopic bolt extending longitudinally within a pocket in the frame. The sear is indicated at

5. The frame *g* is perforated longitudinally to receive a slide or rod *s*. The slide coöperates with the hammer in such a manner that when the hammer fires a cartridge it causes the slide to move into its advanced 60 position, preferably by striking its rear end. The slide is preferably returned to its non-operative position by the action of the ejector lever hereafter described. Said slide rod *s* has at its forward extremity an enlargement *t* furnished with a tooth *u* which, when the slide is in its advanced position, is adapted to project from the curved front surface of the frame or body in relation to which the fore-end moves when the barrel is 70 broken down.

The fore-end carries an ejector hammer *v* which may be of substantially triangular form pivoted at *w* near to its lower vertex, and notched at *x* below its front vertex to 75 accommodate the upper limb of a V-spring *y*, by which said ejector hammer is controlled. At its rear upper vertex the ejector hammer is in the form of a tooth 2 which coöperates with the cartridge case ejector 6. The lower vertex of the ejector hammer comprises a tooth 3 which is adapted to co-operate with the slide tooth *u* which as before mentioned projects if a cartridge has 80 been fired. The engaging surfaces of the respective teeth are so inclined that upon engagement of the teeth an interlocking function is obtained. As a result of this interlocking function the slide *s*, *t* is retained 85 from rearward displacement after the firing hammer 4 has been retracted consequent upon the opening of the gun. The continued opening of the gun results in a forward rocking of the ejector hammer *v* until the engaging face of the tooth 3 has passed a horizontal position. Further opening of the gun causes the engaging face of the tooth 3 to assume a position, such that it forces the slide tooth *u* rearwardly out of engagement; the ejector hammer is accordingly released and is caused by its spring *y* to rock rearwardly into the position shown in Fig. 2; thereby kicking the ejector and causing the latter to eject the cartridge case. The ejector hammer *v* is limited in its ejecting 105 movement, that is to say it is retained in the position shown in Figs. 1 and 2 by the ejector.

The sliding member *s* may be slightly bowed so that it is frictionally retained nor- 110

mally in the position shown in Fig. 1 when its barrel is loaded.

What I claim as my invention and desire to secure by Letters Patent is:—

5 In combination with the frame and the pivotally mounted barrel of a firearm, a movable cartridge ejector carried by the barrel, a pivotally mounted spring actuated ejector hammer also carried by the barrel 10 and having a tooth, and a cocking element for the ejector hammer and comprising a rod slideable longitudinally in a bore in the frame and movable forwardly by the firing hammer, said rod having an enlargement at 15 its front end and a tooth on the front side of said enlargement, the tooth of the said cock-

ing element coacting with the tooth of the ejector hammer to move said ejector hammer to cocked position during initial breaking movement of the barrel, then moving past 20 and disengaging said tooth of said ejector hammer and releasing the latter as the barrel reaches fully broken position, and said tooth of the ejector hammer reengaging and exerting camming action on the tooth of the 25 cocking element to move said element rearwardly in the path of the firing hammer, when the barrel is returned to closed position.

In witness whereof I have hereunto set my hand.

HARRY HERBERT PAYNE.
